US0D1037566S

(12) **United States Design Patent** (10) Patent No.: **US D1,037,566 S**
(45) Date of Patent: ** Jul. 30, 2024

(54) **HAND DRIER**

(71) Applicant: **ILLE Papier-Service GmbH**,
Altenstadt (DE)

(72) Inventor: **Jochen Bittermann**, Gelnhausen (DE)

(73) Assignee: **ILLE Papier-Service GmbH**,
Altenstadt (DE)

(**) Term: **15 Years**

(21) Appl. No.: **35/516,681**

(22) Filed: **Mar. 9, 2023**

(80) **Hague Agreement Data**

Int. Filing Date: **Mar. 9, 2023**

Int. Reg. No.: **DM/227481**

Int. Reg. Date: **Mar. 9, 2023**

Int. Reg. Pub. Date: **Mar. 24, 2023**

(51) LOC (14) Cl. 28-03

(52) U.S. Cl.

USPC **D28/54.1**

(58) **Field of Classification Search**

USPC D28/12, 54.1, 58; D23/357, 361, 385

CPC F26B 21/004; A45D 20/00; A47K 10/48;

(74) Attorney, Agent, or Firm — LADAS & PARRY LLP;
Malcolm J. MacDonald, Esq.

(57) **CLAIM**

The ornamental design for hand drier, as shown and described.

DESCRIPTION

- 1.Hand drier
- 5.Hand drier
- 6.Hand drier
- 7.Hand drier
- 1.1 : Perspective
- 1.2 : Perspective bottom view
- 1.3 : Front
- 1.4 : Top
- 1.5 : Left
- 1.6 : Right
- 5.1 : Perspective
- 5.2 : Perspective bottom view
- 5.3 : Front
- 5.4 : Top
- 5.5 : Bottom
- 5.6 : Left
- 5.7 : Right
- 6.1 : Perspective
- 6.2 : Perspective bottom view
- 6.3 : Front
- 6.4 : Top
- 6.5 : Bottom
- 6.6 : Left
- 6.7 : Right
- 7.1 : Perspective
- 7.2 : Perspective bottom view
- 7.3 : Front
- 7.4 : Top
- 7.5 : Bottom
- 7.6 : Left
- 7.7 : Right

1 Claim, 27 Drawing Sheets
